Fred Kuehne, Jr., Mattoon, Ill.

Application November 30, 1948, Serial No. 149,885

Term of patent 3½ years

(Cl. D33—14)

To all whom it may concern:

Be it known that I, Fred Kuehne, Jr., a citizen of the United States, residing at Mattoon, in the county of Coles and State of Illinois, have invented a new, original, and ornamental Design for a Table, of which the following is a specification, reference being had to the accompanying drawing, forming part thereof.

Fig. 2 is a side elevational view taken on the line 2—2 of Fig. 1.

Fig. 3 is a cross sectional view taken on the line 3—3 of Fig. 2.

Fig. 4 is an enlarged fragmentary view of the side of the table top, showing the side contour thereof.

I claim:

The ornamental design for a table, as shown.

FRED KUEHNE, JR.
